UNITED STATES PATENT OFFICE.

LAWRENCE J. BURKE, OF CHICAGO, ILLINOIS, ASSIGNOR TO CURTIS LEGER CO., OF CHICAGO, ILLINOIS, A CORPORATION OF ILLINOIS.

DESIGN FOR A DISPLAY PLATEAU.

Application filed June 27, 1927. Serial No. 22,576. Term of patent 3½ years.

To all whom it may concern:

Be it known that I, LAWRENCE J. BURKE, a citizen of the United States, residing at Chicago, Illinois, have invented a new, original, and ornamental Design for Display Plateau, of which the following is a specification, reference being had to the accompanying drawing, forming a part thereof.

In the drawing:—

The figure is a perspective view of a display plateau showing my new design.

I claim:

The ornamental design for a display plateau as shown.

LAWRENCE J. BURKE.
